UNITED STATES PATENT OFFICE.

GARRETT H. HUISING, OF CHICAGO, ILLINOIS, ASSIGNOR, BY MESNE ASSIGNMENTS,
TO AUTOMATIC UTILITIES CO., A CORPORATION OF ILLINOIS.

LOOSE-LEAF DEVICE.

1,197,492.

Specification of Letters Patent. Patented Sept. 5, 1916.

Application filed December 29, 1911. Serial No. 668,442.

To all whom it may concern:

Be it known that I, GARRETT H. HUISING, a citizen of the United States, residing in the city of Chicago, county of Cook, and 5 State of Illinois, have invented a certain new and useful Improvement in Loose-Leaf Devices, of which the following is the specification.

My invention relates to that class of devices which are designed to elevate a card or group of cards above the normal position of the remaining cards. Devices of this character with which I am familiar are subject to numerous objections.

15 My invention has for its object to overcome these objections by providing an improved construction where needed, for example, in devices of this class in which the rising bar is elevated by means of toggles and are provided with rollers on the ends of the rising bars for the purpose of overcoming the friction caused by pressure upon the indicating key or button are subject to the objection that while this accomplishes the 25 result sought it makes it very easy for the bars to move laterally as they are elevated, this result being materially assisted by the unequal, insufficient or inadequate spring pressure provided. The result of this is that 30 when the pressure upon the key is released the bar instead of falling into place strikes upon the next adjacent bar on one side or the other and in order to get it into its proper place it is frequently necessary to 35 remove all of the cards from the box. I have designed means for overcoming this objection, which consists of providing guides in which the rollers run. Another objectionable feature is due to the difficulty of returning the bars to their normal position. Various spring and gravity devices have been 40 employed for this purpose all of which are subject to one or more objections. I have produced a means of applying spring pressure 45 sure to the bars in such a manner as to insure their positive return to position in every instance, and my device will produce an even and equal pressure upon the rising bar whether it is in the center or extreme 50 edge of the card index box. Practice has shown that in devices of this kind it is necessary to provide some sort of a cushion along

the inner walls of the sides of the box. Spring-pressed plates and felt cushions have been employed for this purpose.

55 My invention has for its further object to provide a new and improved form for securing the felt cushion in the box so that it can be quickly and easily replaced when worn.

60 My invention also has for its further object to provide a new form for the keyboard of the machine so that all of the characters upon the keys shall be visible at a glance.

65 My means of accomplishing the foregoing may be more readily understood by having reference to the accompanying drawings, which are hereunto annexed and are a part of this specification, in which:

70 Figure 1 is a vertical section of a loose-leaf card index box, fitted with my improvement. Fig. 2 is a top or plan view of the same, with the cover omitted. Fig. 3 is a cross section taken on the line *z z* in Fig. 1. Figs. 4 and 5 are detail views of the guide 75 for the rollers on the rising bars. Fig. 6 is a detail view of the means for securing the felt. Fig. 7 is a cross section taken on the line *A A*. Fig. 8 is a detail view in cross section of the felt and retainer. Fig. 9 illustrates a perspective view of one end of the frame; Fig. 10 illustrates a plan view of one end of the frame with one end of the front wall secured thereto.

80 Similar reference numerals refer to similar parts throughout the entire description.

85 As shown in the drawings, 1 is the box or containing case having a plurality of cards 2 fitted therein, the cards 2 being omitted in some views for the sake of clearness. These 90 cards are provided with pins (not shown) which are detachably secured thereto and are adapted to be engaged by the rising bars on their upward movement.

95 3 is the longitudinally movable bar, the upper end 4 of which is secured to a pin 7 upon the outer end of which is mounted an indicator button or key 8.

100 9 and 10 indicate toggles by means of which the longitudinally movable bars are operatively connected to the rising bar 11. Rollers 12 are mounted in the ends of the rising bars 11 and run in grooves 14 formed in the guide 13. As more clearly seen in the

detail view, the grooves 14 are formed in a plate of metal 13, there being a plurality of the grooves 14 to which are fitted the rollers 12. The plate 13 is secured to the inner side 5 of the end wall 15 of the casing 1. The result of this construction is obvious. When pressure is exerted upon the keys 8, the pin 7 is moved inwardly carrying with it the longitudinally movable bars 3, which through 10 the medium of the toggles 9 and 10 operate to elevate the rising bars 11, the guides 14 insuring the vertical travel of the roller 12 and preventing the possibility of any lateral movement of the latter. The rising bars and 15 the longitudinally movable bars are located in the bottom of the box and surrounded by a frame 16, the sides of which form shoulders upon which the outer edges of the cards 2 rest. The front wall 17 of the frame is 20 detachably secured to the frame and to the walls of the box. This wall 17 serves to prevent the cards 2 from being placed far enough forward in the box to interfere with the inward movement of the pin 7. It is 25 made detachable to permit of the ready removal or insertion of the bars for the purpose of assembling or repair, its lower part being mounted in slots 50 formed in the sides of the frame 16 and it has lugs 51 at 30 its upper part which are secured to the box by means of screws 52 or any other convenient form of fastening.

On the side walls 18 and 19 are mounted strips 20 and 21, which are formed with recesses intermediate their adjacent edges and the wall of the box. In this recess is mounted a plate 22 formed of suitable material, the sides 23 of which are folded upon themselves. A strip of felt 24 of the desired 35 thickness is mounted upon the said plate, the edges of the felt being secured to the plate by being compressed between the folded edges 23 and the plate 22. This plate is then slipped into the recess between the side 40 walls of the box and the strip 21. The strip 20 is then placed in position so that its lower edge engages the edge 23 of the plate 22. The strip 20 is then secured to the wall of 45 the box preferably by means of screws 25, although it is obvious that any convenient 50 form of fastening may be employed for this purpose.

A good deal of trouble has been found 55 in holding the pins 7 in perfect alinement, owing to the fact that they are usually mounted in the front wall of the box 1 or they are mounted in bearings which are in turn mounted on the front wall of the box, which being made of wood affords but an 60 insufficient hold. The result of this construction is that when the box has been in use for a short period of time, the bearings loosen and the pins get out of alinement, materially increasing the friction required 65 to operate the device. I have avoided this

objection by providing a metal plate 26, which is fixedly mounted upon the front wall of the box 1, in which are journaled the pins 7. A similar plate 27 of metal is secured to the inner side of the front wall 70 of the box and the pins 7 are slidably mounted in these two plates. This insures their remaining in perfect alinement at all times. The keys are arranged in three rows, the upper row being the shortest, each succeeding row extending slightly beyond the 75 next upper row and the keys themselves are beveled as clearly seen in Fig. 1. The characters or indicating letters being stamped on this beveled portion presents the entire 80 keyboard to view at a glance without the necessity of getting on a level with the keyboard in order to see the letters or characters on the keys.

The device for insuring an even pressure 85 upon the rising bars for the purpose of returning them to their original position, is illustrated in Fig. 3. It consists of a bar 46 which has two upwardly extending stems 28 and 29 which are slidably mounted in 90 a frame formed of four members, upper and lower bars 37 and 30, and side rods 35 and 36, which connect the upper and lower bars to each other at their outer ends.

The top bar of the frame is provided with 95 a lug 41 which may be cast or formed on the bar 37 and provides a fastening by which to secure the frame to the end wall of the box, screws 40 which pass through suitable openings in the lug 41, serving to accomplish 100 this result.

The inward movement of the longitudinally movable bar 3 serves to start the rising bar 11 on its upward movement when it is brought into contact with the bar 46, which 105 resists its further elevation by reason of the fact that the upwardly extending stems 28 and 29 which are slidably mounted in bearings 38 and 39 formed in the bars 30 and 37 which have mounted thereon coil springs 110 44 and 45, a tension being provided on the spring by means of washers 33 and 34 which are secured to the stems 28 and 29, the washers being held in position by means of pins 42 and 43 which pass through the said 115 stems. Additional spring pressure is furnished by means of a flat bow spring 47 which is secured to the center portion of the bar 30 and depends therefrom, and is adapted to engage the bars 46 in its upward movement, but is so arranged so as to be out of contact at the time when the said bar starts 120 its upward movement. This construction permits the bar 46 to start its upward motion easily, but the pressure increases as it 125 is raised so that when released by the user it will be forcibly pressed back into position.

The mounting of the two stems 28 and 29 in the bars 30 and 37 insures constant 130 alinement of the bar 46 and provides for an

even pressure upon the rising bar whether the bar which elevates the bar 46 strikes it at the ends or the center.

Having described my invention, what I regard as new and desire to secure by Letters Patent, is:

1. In a device of the character described, the combination with a casing having a plurality of cards therein, of a frame in which said cards rest, the front wall of said frame being detachably mounted in slots formed in the lower part of the frame and secured to the side walls of the casing.
2. A device of the character described comprising the combination with a casing of a plurality of cards therein, a plurality of card displacers, a plurality of keys secured to pins mounted in the front wall of the casing and operatively connected to the card displacers and adapted to elevate the card displacers, a metal strip secured to the side walls of the casing near the bottom, there being a recess formed by its upper edge intermediate the wall and the strip, a similar strip detachably secured near the top of the box having a recess at its lower edge, a plate formed of suitable material, the sides of which are folded upon themselves and adapted to hold in said recesses, a strip of elastic or compressible material mounted upon said plate, the edge of which is secured thereto by being compressed between the folded edges of the plate.
3. A device of the character described comprising the combination with a casing of a plurality of cards therein, a frame, a plurality of longitudinally movable bars in the bottom of said casing, a plurality of rising bars operatively connected thereto, a plurality of pins mounted in the front wall of the casing and connected to the longitudinally movable bars, a plurality of keys secured to said pins, a bar mounted upon the top of the rising bars when in a normal position, two stems extending upwardly 45 from the said bar, said upwardly extending stems being slidably journaled in the upper and lower members of said frame, which is rigidly secured to the rear wall of the casing, coil springs surrounding said upwardly extending stems exerting a tension to hold said rising bars down and a flat bow spring mounted on the bottom bar of said frame adapted to engage the spring-pressed bar in its upward travel at a predetermined time. 55
4. A device of the character described, comprising the combination with a casing of a plurality of cards in said casing, a plurality of card displacers mounted in said casing, a plurality of pins mounted in rows 60 in the front wall of the casing, said pins being operatively connected to the card displacers, keys mounted on the said pins, each succeeding row of said pins being longer than the next adjacent upper row. 65
5. In a card-index, a case, cards arranged in said case in groups, independently operable means for elevating said groups, and friction means for holding the groups in elevated position. 70
6. In a card-index, a case, cards arranged in groups, lifting bars for the cards of the respective groups, actuating means for the lifting bars, and means engageable frictionally with the ends of the cards for holding the same in elevated position. 75
7. In a card-index, a case, cards arranged in said case in groups, independently operable means for elevating said groups, means for restoring said means to normal position, 80 and means for holding the groups in elevated position.

In witness whereof I have signed the foregoing specification.

GARRETT H. HUISING.
